UNITED STATES PATENT OFFICE.

THEODORE M. FOOTE, OF BROOKLYN, NEW YORK, ASSIGNOR TO GEORGE H. G. WHITNEY, OF SAME PLACE.

PRINTING-TELEGRAPH APPARATUS.

SPECIFICATION forming part of Letters Patent No. 233,407, dated October 19, 1880.

Application filed January 20, 1880.

To all whom it may concern:

Be it known that I, THEODORE M. FOOTE, a citizen of the United States, residing at Brooklyn, in the county of Kings, State of New York, have invented new and useful Improvements in Printing-Telegraph Apparatus, of which the following is a specification.

This invention relates to that class of printing-telegraph instruments in which a type-wheel is driven by a continuously-applied power, and is given a step-by-step motion by means of an escapement operated by an electro-magnet, and in which the impression and paper-moving devices are controlled by electro-magnetism. Its object is to produce telegraphically a printed record in transverse parallel lines upon a strip of paper.

It consists, first, in the combination, with a rotary type-wheel, of devices operated by an electro-magnet for feeding a strip of paper longitudinally athwart the periphery of said wheel, devices operated by an electro-magnet for moving said strip of paper laterally to permit transverse lines to be printed thereon, and mechanism operated by an electro-magnet for bringing the type-wheel and paper in contact to produce a printed record; second, in the combination of a step-by-step type-wheel controlled by electro-magnetism, a printing-pad having a movement toward and laterally by said wheel and operated by an electro-magnet in a main-line circuit, mechanism controlled by an electro-magnet for returning the printing-pad to its starting-point when desired, and devices for feeding the paper longitudinally to receive a new line; third, in the combination, with a type-wheel and an impression pad or roller carrying a strip of paper laterally to receive impressions from said wheel and back to a starting-point, of devices controlled by electro-magnetism for operating said pad or roller, and mechanism controlled by an electro-magnet for bringing said wheel to its initial point or unison coincidently with the return of said pad or roller to its starting-point; fourth, in the combination, with a step-by-step type-wheel driven by continuously-applied power in one direction, and having an escapement-wheel mounted upon its shaft and controlled by a pallet operated by electro-magnetism,

and a clutch for detachably securing said escapement-wheel to said shaft, of devices controlled by an electro-magnet for operating said clutch for disconnecting said escapement-wheel temporarily from said type-wheel shaft, to permit said shaft and type-wheel to rotate independently of the escapement, for the purpose of bringing said type-wheel to its initial or unison point by a free continuation of its movement in the same direction as its step-by-step travel, as will be fully hereinafter described.

In the accompanying drawings, Figure 1 is a front perspective view of my improved instrument. Fig. 2 is a front elevation of the same. Fig. 3 is a rear view of the instrument with its back plate removed to expose the interior. Fig. 4 is a horizontal section on line *xx* of Fig. 2. Fig. 5 is a side elevation viewed from the left. Figs. 6 and 7 are detached perspective views of the escapement and unison devices. Figs. 8 and 9 are diagrams of circuits suitable for operating the instrument.

The letters A A' designate the front and back plates, which support the working parts of the apparatus, and B is the type-wheel, mounted in front of the front plate upon the projecting end of a shaft, C, journaled in said plates. This shaft has fixed to its rear end, near the back plate, a pinion, *c*, meshing with a gear-wheel, *a*, which may be rotated by a cord and weight applied to its shaft, or may receive rotary motion by connection with any suitable continuous motor, so that it will exert a constant force upon the type-wheel shaft, the movement of which is controlled by an escapement consisting of the toothed escape-wheel *D*, carried by a sleeve mounted upon said shaft, and a pallet, *D'*, fixed to an arbor, *d*, and having an upwardly-projecting arm, *d'*, carrying a polarized armature, *E*, between the poles of two electro-magnets, *F F'*, in the same circuit, and arranged to alternately attract and repel said armature by reversals of an electric current through their coils in a well-known manner. The upper end of the arm *d'* plays between adjusting-screws *d''*, which limit the extent of its vibration.

The escape-wheel *D* has, in addition to its peripheral teeth, a set of crown teeth or pins, *100*

e, projecting toward the front plate, A, and from the type-wheel shaft projects a pin, h, which has a lateral projection at its outer end, which engages with the crown pins or 5 teeth e of the escape-wheel when said wheel is forced toward it by the action of a spiral spring, f, coiled around the type-wheel shaft and pressing against the rear end of the sleeve which carries said escape-wheel. The pin h thus serves to lock the escape-wheel to the 10 type-wheel shaft, from which it may be disconnected to permit said shaft to rotate independently at the proper time by means to be hereinafter described.

15 The letter I designates the impression-roller, mounted in a frame, I', through the inner ends of the end bars of which passes a guide-rod, i, which is supported horizontally in front of the front plate, A, by means of studs i', and said 20 frame slides on said rod to carry the roller longitudinally under the type-wheel in a direction parallel with the horizontal diameter of the latter. From the rear longitudinal bar of the frame I' a horizontal rack-bar, I'', projects 25 downward, and its teeth mesh with those of a spur-wheel, k, which is fixed upon the forward projecting end of a shaft, K, journaled in the supporting-plates, and having a ratchet-wheel, k', fixed upon it just inside the front plate, A.

30 Said shaft K has also fixed upon it, near its rear end, an arm, K', to the outer end of which is attached a cord having a weight, k'', attached to its other end, said cord lying in a groove in said arm and passing around its inner end when the arm is turned to the left, so 35 that the weight and cord will always have a tendency to rotate the shaft K to the right, the words "left" and "right" being used with respect to a front view of the apparatus.

40 Into the teeth of the ratchet-wheel k' takes an impelling-pawl, L, which is pivoted to the upper end of an arm, l, projecting from an arbor, l', journaled in the supporting-plates, and having fixed upon it also a lever, m', carrying 45 an armature, m, arranged in front of the poles of an electro-magnet, M, so as to be attracted by said poles, and is retracted therefrom by a spring in the usual manner, and its throw is regulated by an adjustable stop, l''. A suitable spring keeps the pawl L in contact with the ratchet-wheel, and a retaining hooked pawl, L', kept in contact with said ratchet-wheel also by a spring, prevents it from moving backward or to the right. From the end 50 of impelling-pawl L a pin, e', projects rearwardly, and the retaining-pawl L' carries a similar pin, e'', for a purpose which will be hereinafter explained.

When the arbor l' is caused to rock by the 60 action of the magnet M upon its armature it is obvious that the arm l will work the pawl L to impel the ratchet-wheel k' if the throw of the armature-lever m' is so regulated as to permit said pawl L to take into a fresh tooth of said wheel at each vibration of arm l. The 65 movement of the ratchet-wheel, of course, com-

municates motion through shaft K to the spur-wheel k in front of the front plate, and said wheel, meshing with the rack I'', causes the impression-roller frame to travel on its guide-bar i and move the impression-roller under the type-wheel. The movement of ratchet-wheel k' one tooth causes the roller to be moved a proper distance to place the paper in position to receive the impression of a new letter from 75 the type, and the mechanism for producing the impression will be now described.

From near the top of the arm l a bent arm, n, projects rearwardly, and is bent toward the right, its inner end being pivoted to one arm 80 of a bell-crank lever, n', pivoted to a stud projecting from the rear side of the front plate, and having its other arm extended to the right in such position that when moved toward the front plate it will strike the end of pin n'', 85 which extends through an opening in said plate from an arm, N'', which is fixed upon the end of a horizontal rock-shaft, N', journaled in suitable bearings upon the front of the front plate, and having fixed to it two upwardly-extending arms, N³, connected at their tops by a horizontal bar, N. The tops of the arms N³ rest normally against the front plate, and the bar N lies in rear of and forms a guide for a roller or wheel, i², mounted upon the end of a stud, i³, 90 which depends from the roller-frame I' in rear of the rack. Now, when the armature m is attracted by the magnet M, the arm l is carried to the right, and the arm of the bell-crank lever n', which lies alongside the inner surface of the 95 front plate, strikes the pin n'', throwing the arm N'' outward, causing the rock-shaft N' to throw outward the bar N, which, forcing outward also the stud i³, causes the frame I' to swing upward and press the impression-roller I 100 against the periphery of the type-wheel. The teeth of the rack I'' and spur-wheel k are of such length that they will not be disengaged by this movement of frame I'.

Immediately the magnet M ceases to act on 110 its armature the spring retracts it, and all the parts move in the reverse direction to that just described, the roller I falls away from the type-wheel, and the impelling-pawl L moves the ratchet k' one tooth, thus, as before explained, causing the impression-roller to be 115 moved to the left a sufficient distance to carry its paper to a proper point to receive the next impression.

As the shaft K is turned by the action of 120 the impelling-pawl the arm K' is carried to the left, taking up the cord and raising weight k''. Now, when the impression-roller has moved toward the left a proper distance to have a line completed transversely upon the 125 paper it carries, or when otherwise it is desired to return the roller to its starting-point, (which is at the limit of its movement to the right,) and to feed the paper longitudinally, in order to begin a new line, this effect is produced by the following-described devices: 130 The letter O indicates a lifting-lever, one end

of which extends under the pins e' and e'' , projecting from the pawls L and L' , and said lever curves upward and is firmly fixed to the arbor p , which has also fixed to it the lever p' , carrying an armature, P' , of an electromagnet, P . Said lever is also extended to the right past the magnet P , and from its right-hand end an arm, q , extends laterally through a slot, q' , in the front plate, A . Said arm q carries a head, r , to which is pivoted a block, r' , which can swing to the right against the action of a spring, r'' , and forward from said block extends a plate, R .

The right-hand journal of the impression-
15 roller I projects outward beyond the end bar of the frame I' , and has firmly fixed upon it a ratchet-wheel, S , while loosely upon said projecting journal, outside of the ratchet-wheel, is fulcrumed a bell-crank lever, T , the inner
20 arm of which has pivoted to it a pawl, t , which takes into the teeth of the said ratchet-wheel, and to the other arm is fixed a spring, t' , which bears upon said pawl and keeps it in engagement with the ratchet-teeth. From the outer
25 arm of the bell-crank lever a pin, u , projects to the right, and is of such length as to extend across the path of the plate R when the frame I' is at its starting-point, or at the limit of its movement to the right.

30 The strip of paper to be printed upon passes outward over the roller I and under the springs v v , which keep it close upon said roller. The paper strip is preferably drawn from a reel located at such distance below the instrument that the movement of frame I' longitudinally will not interfere with the passage of said strip over the roller in a proper manner.

I have not shown the reel in the drawings, as its proper arrangement will be readily understood without.

When, now, the frame I' and roller I have been moved as far as desired to the left a current of electricity is passed through the coils of magnet P , and said magnet attracts its armature P' , and the rocking of the arbor p in consequence causes the left or inner end of the lifting-lever O to rise, strike the pins e' and e'' , and lift the pawls L and L' out of engagement with the ratchet-wheel k' , which being thus released, the action of the weight k'' and its cord upon the arm K' causes the shaft K to turn rapidly to the right, and the spur-wheel k , acting upon the rack I'' , carries the frame I' back to its starting-point, the pin
55 u striking the plate R and forcing it to the right. When the current ceases to pass, the armature is retracted by its spring in the ordinary manner, the inner end of the lever O falls, the outer end rises, lifting the plate R away from the pin u , when the spring r forces said plate back to left and directly over said pin. A second electrical impulse now passed through the magnet P causes the lever O to move in the same manner as before, and the
60 plate R strikes the pin u , vibrating the bell-crank lever T and causing the pawl t to move

the ratchet-wheel S one tooth, giving the roller I a partial rotation, which carries the paper strip outward longitudinally a proper distance to receive a new line of printing.

70 It will be obvious that by repeating the impulses through the magnet P the paper may be fed as much as desired to separate the matter to be printed from that already printed.

The impression-roller may be covered with 75 an elastic material in the ordinary manner, and the surface of the types on the type-wheel is concave to correspond to the convexity of the roller, so that the impression will be uniform upon the types. The surface of the ink-
80 roller B' should be convex to correspond with the type-wheel.

It will be understood that several instruments of the kind which I am now describing may be used in the same system of circuits, 85 and it is, of course, necessary that the type-wheels of all such instruments shall be kept in coincidence or unison—that is, that all of the type-wheels shall print the same letter at the same time; and in order to practically 90 maintain this relation of the several instruments, it has been found sufficient to provide means whereby their type-wheels may all be brought to a certain point of coincidence at short intervals.

95 In my present instrument I have made provision for bringing the type-wheel of each instrument to its initial point, usually a dot or period before letter A , each time the impression-roller is returned to its starting-point, 100 and this is accomplished by mechanism which I will now describe.

Upon the type-wheel shaft is mounted a sleeve, W , having a limited longitudinal movement upon said shaft, but prevented from turning thereon by the pin h , which, as heretofore described, is fixed in said shaft and passes through a slot, w . The endwise movement of the sleeve toward the front plate is limited by a fixed collar, w' , on the type-wheel shaft, and 110 in the opposite direction by means of the end wall of the slot w ; but this movement is such that when the sleeve is moved rearwardly it can force the escape-wheel D also rearwardly against the pressure of spring f and disengage the crown-pins e from the pin h .

Upon the sleeve W is fixed a disk, X , having in its periphery a lateral V-shaped indentation, x' , the rear wall of which inclines upwardly and rearwardly.

120 To the inner surface of the front plate, A , is fixed a bracket, Y , in which is journaled a vertical shaft, Y' , to the projecting lower end of which is fixed an arm, Y'' , from the end of which a pin, y , extends through a slot, y' , in the front plate. To the top of shaft Y' is secured an arm, Z , the front portion, Z' , of which is hinged to swing upward against a spring, z' , but is prevented from moving downward, and from said hinged portion a pin, z , 125 projects rearwardly toward the disk X .

From the rear bar of the frame I' a pin, I^3 ,

projects toward the front plate, and extends beyond the end and to the left of pin y , which stands in the path of said pin I^3 when the latter moves toward the right.

5 When the frame I' is retracted to its starting-point, as heretofore explained, at the latter part of its movement the pin I^3 strikes the pin y , causing it and the arms Y'' and Z of the shaft Y' to swing rearwardly and the pin z to strike the disk X , forcing the sleeve W against the escape-wheel, and thus moving said wheel also rearwardly until the crown-pins e become disengaged from the pin h . The escape-wheel being thus unlocked from the 15 type-wheel shaft, said shaft is carried rapidly around by the motive-wheel a in the direction of the arrow, carrying the sleeve W and disk X with it, of course, until the indentation x' comes to the pin z , when said pin slips into this indentation, permitting the 20 spring f to force the escape-wheel forward until its crown-pins e become again engaged with the pin h . The escapement-wheel being held by its pallet, the type-wheel shaft then 25 ceases to revolve, and the type-wheel stands at its initial or starting point, and all the instruments in the circuit are in coincidence. The first forward movement now given to the escape-wheel causes the pin z to ride up the 30 inclined wall of the indentation x' (the hinged part Z' of the arm Z permitting this movement) and rest temporarily upon the periphery of the disk X until the frame I' , in its progress to the left, carries its pin I^3 away from the pin 35 y , and permits the arms Y'' and Z to assume their normal positions when the pin z is removed from contact with disk X .

The several armature-levers may be provided with suitable retracting-springs, adjustments, 40 and stops.

The circuits by which the instrument as now described is operated are illustrated by the diagram, Fig. 8, and it will be understood that they are manipulated by means of a suitable 45 transmitting-instrument. The line being in readiness, a current is rapidly reversed over the line-wire 10, through magnets F F' , causing a vibratory movement of the pallet, permitting a step-by-step movement of the escape-wheel until the proper letter of the type-wheel is brought adjacent to the printing- 50 roller, and the circuit is then prolonged in one direction momentarily to permit the magnet M to become sufficiently vitalized to attract its armature m and operate the impression devices and move the paper laterally to a position to receive another letter, as before explained. Reversed currents are then again sent 55 over the line-wire 10 to bring the next desired letter of the type-wheel in proper position, and so on. The pallet not being held by any spring, its armature responds instantaneously to the influence of the magnets F ; but the impulses of the reversed currents are too brief to induce 60 sufficient magnetic power in the cores of magnet M to attract the armature of said magnet;

hence the necessity of the momentary prolongation of the current in one direction.

When a line of printing is completed across the paper, or when, from any other cause, it is 70 desired to print in a new line, the circuit over line-wire 10 is closed and the circuit over line-wire 11 is opened, causing the electro-magnet P to attract its armature P' and operate the mechanism for causing the impression-roller to 75 be returned to its starting-point to feed the paper longitudinally, and to effect the bringing of the type-wheel to its initial or unison point, as before described.

Each transmitting-instrument will be 80 provided with a register or other suitable means for indicating to the operator when a line of printing has been completed by the printing-instruments.

Instead of using the circuits just described, 85 I may arrange them as shown in the diagram, Fig. 9, in which case, after the rapidly-reversed currents over line-wire 10 and magnets F have brought the type-wheel to proper position, the current is broken on said line-wire and immediately opened on lines 11 to operate the impression devices. Then, when it is desired to return the impression-roller to its starting-point, feed the paper longitudinally, and operate the unison devices, a prolonged current in 90 one direction is sent over the wire 10, causing magnet P to attract its armature.

By a simple modification, which will be obvious to persons familiar with telegraphic printing apparatus, the various other devices 100 besides the escapement may be used in connection with a continuously-rotating type-wheel.

Telegraphic instruments have heretofore been constructed to print transverse parallel lines upon a strip of longitudinally-fed paper; 105 but in such instruments the type-wheel has moved laterally to effect the transverse arrangement of the lines, while in my instrument the paper is moved transversely as well as fed longitudinally.

What I claim is—

1. In a telegraphic printing-instrument, the combination, with a rotary type-wheel, of devices operated by an electro-magnet for feeding a strip of paper longitudinally athwart the 115 periphery of said wheel, devices operated by an electro-magnet for moving said strip of paper laterally to permit transverse lines to be printed thereon, and mechanism operated by an electro-magnet for bringing the type-wheel 120 and paper in contact to produce a printed record, substantially as set forth.

2. The combination of a step-by-step type-wheel controlled by electro-magnetism, a printing-pad having a movement toward and laterally by said wheel and operated by an electro-magnet in a main-line circuit, mechanism controlled by an electro-magnet for returning the printing-pad to its starting-point when desired, and devices for feeding the paper into 130 position to receive a new line, substantially as described.

3. The combination, with a type-wheel and an impression pad or roller carrying a strip of paper laterally to receive impressions from said wheel and back to a starting-point, of devices controlled by electro-magnetism for operating said pad or roller and mechanism controlled by an electro-magnet for bringing said wheel to its initial or unison point coincidently with the return of said pad or roller to its starting-point, substantially as described.

4. The combination, with a step-by-step type-wheel driven by continuously-applied power in one direction, and having an escapement-wheel mounted upon its shaft and controlled by a pallet operated by electro-magnetism, and a clutch for detachably securing said escapement-wheel to said shaft, of devices controlled by an electro-magnet for operating said clutch for disconnecting said escapement-wheel temporarily from said type-wheel shaft, to permit said shaft and type-wheel to rotate independently of the escapement for the purpose of bringing said type-wheel to its initial or unison point by a free continuation of its movement in the same direction as its step-by-step travel, substantially as set forth.

5. The combination, with the type-wheel having the escapement-wheel D mounted on its shaft, which is driven by continuously-applied power, of the pallet D', the lever of which carries a polarized armature, the magnets F F', for operating said pallet, the electro-magnet M in the same circuit with said magnets, and the devices for moving the paper laterally and giving the impression, operated by said electro-magnet M, substantially as described.

6. The combination, with the type-wheel having the escape-wheel mounted upon its shaft and controlled by electro-magnetism, the impression-roller frame having the rack I'', the shaft K, carrying the toothed wheel k, meshing with said rack, and the ratchet-wheel k' of the retaining-pawl L', the electro-magnet M, operating armature m, lever l, and pawl L, for impelling said ratchet-wheel in one direction, devices for turning said shaft K in the

reverse direction, and devices operated by an electro-magnet for releasing the ratchet-wheel from its impelling and retaining pawls, substantially as described, and for the purpose set forth.

7. The combination of the shaft K, operating the paper-carrier on its slide in both directions and having the ratchet-wheel k' mounted thereon, the retaining-pawl L', having pin e'', the impelling-pawl L, having pin e', operated by electro-magnet M through intermediate devices, and the lifting-lever O, operated by electro-magnet P, for disengaging said pawls from the ratchet-wheel, substantially as described.

8. The combination of the impression-roller and its frame, moved longitudinally by shaft K through intermediate devices, the ratchet-wheel k', retaining-pawl L', the impelling-pawl operated by an electro-magnet, M, the impression devices operated by same magnet, the lever O, operated by magnet P, to release the ratchet-wheel from its impelling and retaining devices, and the paper-feeding devices, also operated by said lever, substantially as described.

9. The combination, with the type-wheel shaft, driven by continuous power and having the pin h projecting therefrom, of the escape-wheel D, mounted loosely upon said shaft, provided with the crown pins or teeth e, and controlled by electro-magnetism, the spring f, acting to press said wheel forward toward said pin h, the longitudinally-movable sleeve W, having the slot w, embracing said pin, and carrying the disk X, having the indentation x', and the shaft Y', carrying jointed arm Z, provided with pin z and operated by an electro-magnet through intermediate devices, substantially as described.

In testimony whereof I have hereunto set my hand in the presence of two subscribing witnesses.

T. M. FOOTE.
